UNITED STATES PATENT OFFICE

JOHN N. ECONOMOS, OF WASHINGTON, DISTRICT OF COLUMBIA

TIME-CONTROLLED SWITCH

Application filed December 28, 1929, Serial No. 417,139.

This invention relates to time controlled electric switches especially adapted to turn on and off the parking lights of automobiles.

The principal object of the invention is to provide a device of this kind consisting of a clock mechanism and means associated with the clock mechanism to turn on and off an electric switch.

Another object of the invention is to construct a device of this character having means to regulate the time in which to turn on and off the parking light.

Other objects will appear as the disclosure progresses. The drawings are merely intended to indicate a possible embodiment of the invention. It is obvious that the actual needs of manufacture may necessitate certain mechanical changes. It is therefore not intended to limit the invention to the embodiment shown in the drawings but rather to define such limits in the appended claims. For a more general understanding of the invention attention is called to the drawings. In these drawings like reference characters denote like parts throughout the specification.

Figure 1 is a front view of the device.

Figure 2 is a rear view showing the switch operating mechanism in its normal position.

Figure 3 is a fragmentary rear view showing the switch operating mechanism in its second position.

Figure 4 is a fragmentary rear view showing the switch operating mechanism in its third position.

Figure 5 is a section on line 5—5 of Figure 2.

Figure 6 is a section on line 6—6 of Figure 1 showing the clock partly turned around on its pivots.

Figure 7 is a section on line 7—7 of Figure 1.

Figure 8 is a fragmentary detail.

Referring now to the drawings in detail numeral 1 designates a standard alarm clock having the usual minute and hour hands 2 and 3 and the alarm setting hand 4. On the rear is the usual main spring winding handle 5 and the knob 6 for setting the alarm hand. Numeral 7 represents the stem projecting out of the casing used for winding up the alarm

ring mechanism. However, instead of having fastened thereto the usual handle other mechanism is used instead as will be presently described. Likewise on the usual stem 8 used to set the minute and hour hand is fastened other mechanism which will be presently described.

The stem 8 which is a part of a standard alarm clock as noted in Figure 5 makes one complete revolution every hour. To serve the purpose of this invention it is necessary to use a substitute stem 9 which will revolve once a day. To bring about this result a set of reduction gearing is used as follows:

The relatively small driving gear 10 fixed on the stem 8 meshes with a larger gear 11 keyed on the stem 12. At the top of this stem 12 is another small gear 13 which meshes with a larger gear 14 keyed to the bottom of shaft 9. The gears are so proportioned that for each twenty-four revolutions of the driving gear 10 the shaft 9 revolves once.

Attached to the stem 7 is a short arm 15 and a long T-shaped arm 16. This last mentioned arm is used to wind up the spring by an anti-clockwise rotation which in the ordinary alarm clocks provides the motive power for operating the bell ringing mechanism. It also serves another purpose which will be presently described.

Pivoted on the bolt 17 is a fork 18 having a projecting arm 19 at the bottom and a shoulder 20 in one of the fork members. Keyed to the stem 9 is a cam 21 provided with a slot 22 in which fits the end of the lever 23 movable in a guide 24. The opposite end of the lever is attached to an oscillating arm 25 pivoted on the pivot 26 and having a downwardly projecting end 27. Numeral 28 designates a plate of insulating material to which are fastened two contact points 29 and 30. Attached to these contact points are wires 31 and 32 leading to a source of current 33. In series with the contact points and source of current is the parking light 34.

The clock is adapted to be set in the dashboard 35 of the vehicle. The face of the clock is used as an ordinary time piece while the operating and adjusting mechanism is at the

back. In order to get at the back for winding, adjusting and regulating, the clock is arranged so that it can be turned on its pivoting points 36 and 37 as shown in Figure 6. The pivoting mechanism consists of a shaft 38 at the top of the clock and a shaft 39 at the bottom provided with a shoulder 40 and a slot 41. The shaft 38 fits in a hole 41 in the periphery of the circular opening 42 at the top and the shaft 39 fits in a hole 42 at the bottom while the slot 41 registers with the wedge 43. Placed around the shaft 38 is a compression spring 44 for normally pressing the clock downwardly and preventing any vibration of the clock mechanism. It will thus be seen that when the clock is on a level plane with the dash the clock will be normally latched in place due to the wedge and slot construction. When turning around the clock for regulating or winding, the clock will be automatically lifted against the spring 44 until the shoulder 40 rides on the edge of the wedge 43. When turned back in the position shown in Figure 1 the wedge will slip back again into the slot 41.

The operation of this device is as follows. Say it is desired to turn on the parking light at 6 p. m. and turn it off at 6 a. m. The arm 45 keyed on the stem 9 is first placed in the position as shown in Figure 2, the alarm setting hand in the position as shown in Figure 1 and the main and secondary springs wound up. The main spring is wound up by the handle 5 and the secondary spring by the arm 16. When the hands 2 and 3 indicate 6 o'clock the stem 7 in the well known manner as is usual in alarm clocks will commence to revolve clockwise. The arms 15 and 16 keyed to this stem will revolve with it until the end of the arm 15 is caught on the shoulder 20 of the fork as indicated in Figure 3. In this position the T-shaped head of the arm 16 will bridge the gap between the contacts 29 and 30 as shown in Figure 3 and close an electric circuit and thereby light the parking light 34. In the meantime the arm 45 will revolve until the end will come in contact with the arm 19 of the fork and swing the fork in the position shown in Figure 4. Although the arm 15 will be released from resting on the shoulder 20 of the fork the said arm and its associated parts will not move for the reason that by this time the hands 2 and 3 have advanced approximately eight hours. It might be said here that in the ordinary alarm clocks when the alarm is set off the alarm will ring for approximately five minutes. As soon as the five minutes are over the usual trip mechanism common to these clocks will stop the alarm and consequently the stem 7 which is a part of the standard alarm clock will be kept from revolving. As the clock mechanism used in this device is of this kind, the arms 15 and

16 will not move until it is twelve hours later or 6 a. m. At this hour the stem 7 will commence to revolve again until the end of the arm 15 points to the left and is caught by the end 27 of the lever 25 as shown in Figure 8 and the rotation stopped. When the arm takes this position the fork will be caused to move back to its original position as shown in Figure 2 by the end of the arm sliding against the left portion of the fork.

The lever 25 is oscillated by the action of the cam 21. When the arm 45 is in the position shown in Figure 2 corresponding to six o'clock the cam will cause the lever 25 to swing to the left and allow the arm and its associated parts to go through the same movements again. The parking light burns only when the arm 16 is in the position shown in Figures 3 and 4 or from six a. m. to six p. m. However, the setting can be regulated by moving the hand 4 so that the parking light can be turned on earlier or later as the case may be. The cam 21 controls the movement of the levers 23 and 25 so that about half of the time the lever 25 is in the position shown in Figure 2 and the other half of the time in the position shown in Figure 4.

Once the clock springs which correspond to the main and alarm springs of the standard alarm clocks are wound up the action of the device is entirely automatic.

If the alarm setting hand is set at 6 o'clock when that time comes the release mechanism used in the standard alarm clocks will allow the lever 16 to turn until it bridges the gap between the contact points 29 and 30 and thereby turn on the parking light. When it is twelve hours later or six o'clock again the lever 16 will revolve back to its original position as shown in Figure 2 and the parking light will be turned off. The arms 15 and 16 revolve together as they are both keyed to the same shaft.

This device is not only limited to parking lights but can be used with slight modifications to turn on and off gas burners or control other mechanism.

Having described my invention, I claim:

1. In a time controlled switch of the class described, the combination of an arm revolving once every twenty-four hours, of a pivoted lever for making and breaking the current of said switch, a cam revolving in unison with said arm, means operated by said cam for latching and unlatching the said lever at predetermined intervals in order to turn on and off the electric current and means operated by said arm for latching and unlatching said lever at different intervals of time than the first mentioned means.

2. In a time controlled switch of the class described, the combination of an arm revolving once every twenty-four hours, of a cam revolving in unison with said arm, a horizontal lever actuated by said cam, a vertical

- cal pivoted lever having a downwardly bent end movable by said horizontal lever, an oscillating fork actuated by said arm, a pivoted switch element, means to latch and unlatch the switch element by said vertical lever at a predetermined time, and means to latch and unlatch said switch element by said oscillating fork at different intervals of time than the first mentioned latching means.
- 10 In testimony whereof I affix my signature.

JOHN N. ECONOMOS.
